(57) **CLAIM**

The ornamental design for a barrel dispenser as shown and described.

DESCRIPTION

FIG. 1 is a front, right-side and top perspective view of a barrel dispenser showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a cross-sectional view taken in the direction of line **8-8** in FIG. 2; and,

FIG. 9 is a cross-sectional view taken in the direction of line **9-9** in FIG. 2.

The dot-dash broken lines in FIG. 2 show the cross sectional lines for FIGS. 8-9 and form no part of the claimed design.
